MACHINE FOR HANDLING CANNED GOODS

Application filed March 6, 1931. Serial No. 520,697.

This invention relates to an improved machine for handling canned goods, of such a design that the canned goods will be carried to and through a discharge opening of a chute, and deposited on a conveyor (not shown), which in turn will carry the canned goods to an automatic boxer or to a labeling machine.

In canning factories, after the canned goods leave the canning machines it is necessary to pack the canned goods in boxes or crates, and to facilitate this work it is the purpose of the present invention to provide a machine for arranging the canned goods in sequential order, so that they may be easily carried on a conveyor to a point to be packed. In other words the canned goods may be emptied into a hopper chaotically, and from which they are carried by a conveyor upwardly to a compartment of the machine and automatically deposited upon a second conveyor, and then upon a vibrating or shaking cradle, the various cans tumbling or falling over each other during this course, and as the canned goods are passing through the machine, they become gradually and automatically arranged in order lying down on their sides, so that they can be easily and conveniently in sequential order carried to a point to be packed.

In handling the canned goods, the invention has for its purpose to provide means to retard the canned goods periodically, before they pass on to feed rolls, which act to place the cans one behind the other, on to a third conveyor, which carry the canned goods to a chute, through which they pass in lying down positions.

When the canned goods are passing from the feed rolls on a conveyor, some are lying down and some are standing on end, and in this instance it is the aim to arrange all the cans in a lying down position on the conveyor. At a point beyond the feed rolls 45 abutment means is provided to knock those

cans which are standing on their end over upon the sides. To facilitate this the machine also includes means to retard the cans one at a time, while a preceding can is being tilted over upon its side. The reason for retarding a can at this point is to prevent the can being tilted from striking the can in the rear.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawings and claimed.

In the drawings:

Figure 1 is a view in side elevation of the improved machine for handling canned goods from the canning machine to a point or location where the canned goods are packed for shipment, illustrating a hopper and a portion of a conveyor immediately adjoining the receiving compartment of the machine proper, the machine being constructed in accordance with the invention.

Figure 2 is a plan view of Figure 1 omitting the hopper shown in Figure 1.

Figure 3 is a sectional view on line 3—3 of Figure 1.

Figure 4 is a sectional view on line 4—4 of Figure 2, more clearly showing the passage of the canned goods through the receiving compartment.

Figure 5 is a sectional view on line 5—5 of Figure 1 illustrating the screw feed rolls as well as the carrier belts in the guide channels for the canned goods.

Figure 6 is an enlarged plan view of a portion of the channel way of the machine, at a point beyond the screw feed rolls, illustrating the intermittent operating checking means for the canned goods in its passage.

Figure 7 is a side elevation of Figure 6.

Figure 8 is an enlarged sectional perspective of a retarding gate or device at one end of the canned goods receiving compartment for preventing too many canned goods passing from the receiving compartment to and between the screw feed rolls.

Figure 9 is an enlarged detail sectional view of the terminal of the chute where the cans are discharged in order to be packed.

Referring to the drawings 1 identifies the base frame of the machine for handling canned goods, and this frame merges into a superimposed frame 2 which includes a canned goods receiving compartment 3, and to be disposed a requisite distance from one end of the machine is a hopper 4, which receives the canned goods in a chaotic order from any conventional type of canning machine (not shown). In the lower part of the hopper 4 the lower end of an inclined conveyor 5 has its operating roll 6 journaled in bearings of the hopper, in such wise as to receive and convey the canned goods upwardly and out of the hopper. Supporting brackets 7 are carried by one end of the superimposed frame 2, and journaled in bearings thereon is the upper operating roll 8 of the conveyor 5. A suitable inclined guide 9 extends from a point immediately adjacent the roll 8, for guiding the canned goods into the receiving compartment of the superimposed frame.

Mounted in the receiving compartment is a horizontal conveyor 10, the rolls 11 of which are journaled in bearings 12 on the interior of the compartment. This conveyor 10 is immediately adjacent one end of the guide 9, so that when the canned goods reaches the end of the guide they deposit onto the conveyor which carries the goods to a shaking cradle 13, which is pivoted at one end adjacent one end of the conveyor 10.

This shaking cradle may be of any conventional construction, though it comprises a frame 15 and a flooring 16. The end 17 of the flooring of the cradle terminates in a plurality of varying lengths of fingers, the purpose of which is to deliver the canned goods to and between the screw guide rolls 70 and 71 at different points. In other words some of the fingers act to deposit the canned goods immediately at one end of the screw guide rolls, while the medium length of fingers deliver certain other of the canned goods a slight distance beyond, whereas the maximum length of fingers deliver certain other of the canned goods a greater distance beyond at a point adjacent the base portion of the superimposed frame 2. Just above the under frame structure a crank shaft 19 is journaled in bearings 20, and connected to the cranks 21 thereof are links 22, which in turn are pivoted at 23 to blocks 24 bolted or otherwise secured to angle beams 25, which constitute reinforcements for the frame 15 of the shaking

cradle. Obviously when the crank shaft 19 rotates, the links impart up and down movements to one end of the cradle, acting to shake or vibrate the canned goods in order to arrange them in symmetrical order as much as possible.

In order to prevent the canned goods from leaving the cradle too rapidly a suitable retarding gate 26 is provided at one end of the receiving compartment. This gate is pivoted at 27 and is adapted to move to varying open positions as will be hereinafter obvious. Carried by the lower edge of this retarding gate is a buffer foot piece 28, which is provided with a rubber head 29 shown clearly in Figures 4 and 8. The ends of this buffer foot piece are mounted in the guides 30, which are carried by the end edges of the gate. The foot piece is carried by the headed rods 31 which pass through the thickness of the gate as shown at 32, and the ends of the headed rods terminate in openings formed in the gate. The ends of the headed rods have retaining nuts 34, which can be adjusted to limit the downward movement of the rods and therefore limit the downward movement of the buffer foot piece. Obviously the foot piece yields upwardly according to the position of the gate and according to the number of canned goods passing under the foot piece. Suitable springs 35 are connected to the plates 36 carried by the gate, and in turn connected to the pins 37 projecting from the sides of the receiving compartment 3. These springs tension the gate and act to prevent the gate from too freely opening. Journaled in bearings of the under base frame structure 1 is a shaft 38 provided with a pulley 39 thereon and having arms 40 on its opposite ends, there being a belt 41 passing about the pulley, for the purpose of transmitting power to the shaft.

In bearings of the lower part of the frame 1 a shaft 42 is journaled, and on one extreme end of the shaft a drive pulley 43 is carried, adapted to receive power from any suitable source, such as a motor or the like (not shown). Also on the shaft 42 near the center thereof a pulley 44 is mounted and about which the belt 41 travels. This belt 41 in turn passes about the pulley 39. In this manner power is transmitted to the shaft 38.

Pivoted to the arm 40 and to an ear of an angle plate 46 on the gate is a pitman 47, and by means of this connection, when the shaft 38 rotates movements are imparted to the gate, allowing it to move to varying open positions against the action of the springs 35. In this manner the passage of canned goods from the shaking cradle may be controlled, that is the rapidity with which the canned goods may pass from the cradle to and between the screw guide rolls.

The retarding gate has auxiliary retard-

ing elements 48, which are hinged at 49 to the inner face of the gate 26, as shown clearly in Figures 3 and 4. These elements are located more or less in position adjacent the ends of the minimum length of fingers 50 of the shaking cradle, while the gate 26 operates more in conjunction with the medium and maximum length of fingers 51 and 52, to control the passage of the canned goods. Suitable curved rods 53 are carried by the gate 26 and engage through the auxiliary retarding elements 48, and surrounding the rods intermediate the elements 48 and the gate 26 are coil springs 54, which act to tension the elements 48 and hold them against the circular abutment plates 56. The abutment elements 48 will therefore yield in the direction of the gate 26, according to the number of canned goods passing along the shaking cradle.

The connecting rods 47 each comprising two sections 57 and 58, the latter being pivoted to the plate 46 on the gate while the former is pivoted to the arm 40 and is telescopically united in a tubular portion 59 of the latter. The purpose of this connection is that the arm 40 operates to move the rod in the direction of the arrow *a*, and thereby tend to open the gate 26, due to there being a certain amount of frictional contact between the tubular portion 59 of the section 58 and the section 57 on the return movement of the arm, the springs 35 act to return the gate toward its closed position. The co-operation of the parts of the rod 47 together with the springs 35 act to so control the gate 26 as to prevent clogging of the canned goods in its passage along and when leaving the cradle.

Mounted on the frame 1 just beyond the discharge of the compartment 3 and substantially immediately below the fingers of the cradle are channel guides or troughs 60 and 61, which consist of the remote inclined guide walls 62 and the intermediate inclined guide walls 63. The lower portions 64 of the guide channels or troughs have parallel guide walls. Supports 65 and 66 support the inclined walls 62 and 63.

In suitable bearings 67 on the frame 1 at the ends of the guide channels or troughs are shafts 68 and 69 carrying screw rolls 70 and 71. Extending spirally around the circumference of the rolls are ribs 72, which are V shaped in cross section. The screw rolls are in pairs, and the V shaped ribs act to distribute the canned goods on the conveyor 73, which feeds them toward the chutes 74.

The rear ends of certain of the shafts 68 and 69 are provided with pulleys 75, while the rear ends of certain other of the shafts 68 and 69 have pulleys 76. The pulleys 75 and 76 in pairs are connected by the belts 77. Adjacent the pulleys on the ends of certain of the shafts 68 and 69 pulleys 78 and 79 are mounted, and these pulleys are connected by

belts 80 and 81 to pulleys 82 on the shaft 42, which carries the drive pulley 43, and thereby in this manner imparting movement to the shafts 68 and 69 and therefore the screw rolls 70 and 71, which rotate in the direction of the arrows *b*. These screw rolls act to distribute the canned goods on to the conveyor belts 73, the conveyor belts 73 operate to carry the canned goods toward chutes 74.

Journalized in bearings 83 of the frame 1 are shafts 84 and 85 which carry pulleys 86, about which the conveyor belts 73 operate for carrying the canned goods toward the chutes 74. On one end of the shaft 84 a pulley 87 is carried, engaged by a belt 88, which in turn passes about a pulley 89 on the shaft 42, for the purpose of transmitting power to the conveyor belt 73.

On one end of the shaft 19 a pulley 90 is mounted, and engaging therewith is a belt 91, which passes about a pulley 92 on the shaft 42, thereby transmitting motion to the shaft 19 and hence to the shaking cradle, for the purpose of agitating the canned goods on the cradle.

It is obvious that when the canned goods enter the guide channels or troughs 60 and 61 and finally are carried by the conveyor belts 73, some of them will be lying down and some standing on end. Therefore it is the purpose to cause such of the canned goods to lie down on the conveyor belt, and in order to accomplish this it is necessary to not only keep the canned goods separated properly at a point before they leave the conveyor belt 73, but also to retard certain of the canned goods, while a preceding can is being tilted over on its side by means of a yieldable abutment 93.

The opposed walls 94 of the lower parts of the guide channels or troughs have extension side walls 95, as in Figures 4 and 6, and as also shown in Figures 2 and 4, and formed in one of each of these extension side walls 95 is an opening 96, as more clearly shown in Figures 6 and 7, and passing vertically through the wall are pins or rods 97 and 98. On the pin or rod 97 an arm 99 is fixed, and on the lower end of the pin or rod 97 a coil spring 100 is mounted, the construction and arrangement of which is such as to tension the rod or pin 97 and hold the arm 99 against a stop pin 101, the arm 99 protruding through the slot or opening 96 in the path of one of the canned goods. On the upper end of the pin or rod 98 an arm 102 is fixed, while the lower end of the rod or pin 98 carries a coil spring 103, the construction and arrangement of which is such as to hold the arm 102 normally against the stop pin 104. Hinged at 105 to each wall having a slot or opening 96 is a holding detent 106, which is tensioned by the leaf spring 107. By referring to Figures 6 and 7 the slot or opening 96 has an intermediate wall 108, thereby dividing the opening 130

or slot 96 in two portions 109 and 110. Journaled on the pin or rod 98 and located in the portion 110 of the slot or opening 96 is a cam 111, the action of which is to retain the holding detent 106 in a normal position as indicated in dotted lines in Figure 6, that is to say when there are no canned goods passing through the channel. In other words while the springs 100 and 103 are in weak tension, just enough to hold the arms 99 and 102 in contact with the stop pins 101 and 104, the spring 103 is of sufficient tension to overcome the action of the lock spring 107 and thereby retain the holding detent in the position indicated in dotted lines at 112.

As the canned goods pass through extension portions of the channel guides or troughs, that is those portions caused to be formed by the walls 95, those that are lying down on their sides, and particularly should it be the very first one, it will engage with the arm 99 and pass under the arm 102. However should the very first canned goods be standing on its end and the next one lying down, the one standing on its end will sweep by the arm 99 against the action of the spring 100, and will then engage with the arm 102, moving it against the action of the spring 103, hence operating the cam 111 out of the way of the holding detent 106, allowing the detent to move in the path of the body of the arm 99, holding it in such position to prevent the passage of the next lying down canned goods as in Figures 6 and 7. The canned goods standing on end will continue to travel owing to being conveyed by the belt 73, moving the arm 102 sufficiently so that the can will pass it, and by the time that the can goods standing on end reaches and has been tilted over on its side by the yieldable abutment 93, the arm 102 has moved back in engagement with the stop pin 104, and consequently having caused the cam 111 to remove the holding detent 106 from the path of the arm 99, in which case the next lying down canned goods will merely sweep by the arm 99. Should there be two or possibly three adjacent canned goods each standing on end approaching the arm 99 and then the arm 102 the actions of the arms are identical as when the preceding can is on end and the next one following is lying down.

The yieldable abutment 93 is hinged at 113 to one of the bars of the chute 74. In other words an end 114 of one of the bars of the chute 74 is free and unattached and the hinge connection 113 is carried by the free and unattached portion of the bar. The abutment 93 has an upturned portion 115. A spring 116 is mounted on a headed stud 117 which is carried by the hinged yieldable abutment and passes through the extremity of the free and unattached portion 114. The spring 116 tensions the abutment, to hold it in the position shown in Figures 1 and 4. However

when one of the canned goods strikes the abutment it will yield to a certain extent against the action of the spring 116.

The chute 74 extends slightly beyond one end of the frame 1, and when the canned good reaches the terminal of the chute it discharges therefrom at a point identified at 118, which is no more or less than an opening. This opening 118 is formed by one of the bars of the chute terminating at 119. The various bars forming the side walls of the chute 74 are held in spaced positions in cylindrical formation by rings 121 and 122, which are in turn bolted to the bars. It will be noted that one of the bars having the free and unattached portion 114 has its extremity beyond the ring 122 bent downwardly at 123 with its bent extremity 124 bolted at 125 to the ring 122. A buffer 126 is located at the end of the chute 74 immediately in close position to the ring 122. This buffer is operatively associated with the bent portion 123 of one of the bars, and is conveniently spring tensioned at 127, so that when each of the canned goods reaches the opening 118 it will strike the buffer to relieve the force of travel, and then drop through the opening 118, upon a suitable conveyor (not shown) so that the goods can be carried to an automatic boxing or crating machine. When the canned goods drop through the opening they will fall on their sides upon such conveyor. The shaft of the operating roll 8 around which the conveyor belt 5 passes has at one of its ends a pulley 129, with which a belt 130 engages. The belt 130 in turn engages with and operates a pulley 128 on the end of one of the rolls 11. It is obvious that the shaft of the roll 6 may receive power from any suitable source, which is transmitted to the belt 5 and thence to the belt 130 and the conveyor 10.

The invention having been set forth, what is claimed is:

1. In a machine for handling canned goods, a frame having a receiving compartment and provided with means for delivering the canned goods chaotically thereinto, said compartment having a discharge end and an agitating cradle constituting the bottom of the compartment for agitating the canned goods toward the discharge end, means for regulating passage of the canned goods through the discharge end, said frame having guide channels or troughs just beyond the discharge end, the end portion of the agitating cradle adjacent the discharge end having means for regulating the canned goods into the channels or troughs in substantial equal quantities, conveying chutes beyond an communicating with the guide channels or troughs for receiving the canned goods, and means in said channels just prior to reaching the chutes for arranging the canned goods in sequential order lying on their sides, whereby

they may enter the chutes end for end, said means at the end edge of the cradle comprising varying lengths of fingers.

2. In a machine for handling canned goods, a frame having a receiving compartment and provided with means for delivering the canned goods chaotically thereinto, said compartment having a discharge end an agitating cradle constituting the bottom of the compartment for agitating the canned goods toward the discharge end, means for regulating passage of the canned goods through the discharge end, said frame having guide channels or troughs just beyond the discharge end, the end portion of the agitating cradle adjacent the discharge end having means for regulating the canned goods into the channels or troughs in substantial equal quantities, conveying chutes beyond and communicating with the guide channels or troughs for receiving the canned goods, and means in said channels just prior to reaching the chutes for arranging the canned goods in sequential order lying on their sides, whereby they may enter the chutes end for end, and means in the guide channels or troughs for feeding the canned goods therethrough, and unitary means operatively connecting with the cradle and the feeding means for transmitting motion thereto, the construction and arrangement of the troughs or channels at a point substantially adjacent the discharge end of the cradle being such as to permit the canned goods to enter the troughs in substantial equal amounts.
3. In a machine for handling canned goods, a frame having a receiving compartment and provided with means for delivering the canned goods chaotically thereinto, said compartment having a discharge end an agitating cradle constituting the bottom of the compartment for agitating the canned goods toward the discharge end, means for regulating passage of the canned goods through the discharge end, said frame having guide channels or troughs just beyond the discharge end, the end portion of the agitating cradle adjacent the discharge end having means for regulating the canned goods into the channels or troughs in substantial equal quantities, conveying chutes beyond and communicating with the guide channels or troughs for receiving the canned goods, and means in said channels just prior to reaching the chutes for arranging the canned goods in sequential order lying on their sides, whereby they may enter the chutes end for end, said means at the end edge of the cradle comprising varying lengths of fingers, the construction and arrangement of the troughs or channels at a point substantially adjacent the fingers being such as to permit the canned goods to enter the troughs in substantial equal amounts.
4. In a machine for handling canned goods, a frame having a receiving compartment and provided with means for delivering the canned goods chaotically thereinto,

said compartment having a discharge end an agitating cradle constituting the bottom of the compartment for agitating the canned goods toward the discharge end, means for regulating passage of the canned goods through the discharge end, said frame having guide channels or troughs just beyond the discharge end, the end portion of the agitating cradle adjacent the discharge end having means for regulating the canned goods into the channels or troughs in substantial equal quantities, conveying chutes beyond and communicating with the guide channels or troughs for receiving the canned goods, and means in said channels just prior to reaching the chutes for arranging the canned goods in sequential order lying on their sides, whereby they may enter the chutes end for end, and means in the guide channels or troughs for feeding the canned goods therethrough, and unitary means operatively connecting with the cradle and the feeding means for transmitting motion thereto, the construction and arrangement of the troughs or channels at a point substantially adjacent the discharge end of the cradle being such as to permit the canned goods to enter the troughs in substantial equal amounts.

5. In a machine for handling canned goods, a frame having a receiving compartment for the canned goods, and means for delivering the canned goods chaotically into the compartment, said compartment having a discharge end, guide channels or troughs just beyond and slightly below the discharge end, yieldably mounted gates in the discharge end, an agitating cradle constituting the bottom of the compartment for agitating the canned goods toward the discharge end, the end of the cradle adjacent the discharge end having varying lengths of fingers acting to co-operate with the gates for regulating the canned goods in substantial equal amounts into the guide channels or troughs, feed means in the channels or troughs, chutes beyond and communicating with the guide channels or troughs, and means in the guide channels or troughs for arranging the cans in sequential lying down positions on the feed means just prior to entering the chutes.

6. In a machine for handling canned goods, a frame having a receiving compartment for the canned goods, and means for delivering the canned goods chaotically into the compartment, said compartment having a discharge end, guide channels or troughs just beyond and slightly below the discharge end, yieldably mounted gates in the discharge end, an agitating cradle constituting the bottom of the compartment for agitating the canned goods toward the discharge end, the end of the cradle adjacent the discharge end having varying lengths of fingers acting to co-operate with the gates for regulating the canned goods in substantial equal amounts.

amounts into the guide channels or troughs, feed means in the channels or troughs, chutes beyond and communicating with the guide channels or troughs, and means in the guide channels or troughs for arranging the cans in sequential lying down positions on the feed means just prior to entering the chutes, and means for operating the gates to varying open positions to insure regulating the canned goods into substantial equal amounts when discharging into the channels or troughs.

In testimony whereof I affix my signature.
CARL B. STRETCH.
